UNITED STATES PATENT OFFICE.

OSCAR JUNGGREN, OF SCHENECTADY, NEW YORK, ASSIGNOR TO GENERAL ELECTRIC COMPANY, A CORPORATION OF NEW YORK.

MULTISTAGE TURBINE.

No. 834,476.

Specification of Letters Patent.

Patented Oct. 30, 1906.

Application filed May 28, 1904. Serial No. 210,167.

To all whom it may concern:

Be it known that I, OSCAR JUNGGREN, a citizen of the United States, residing at Schenectady, county of Schenectady, State of New York, have invented certain new and useful Improvements in Multistage Turbines, of which the following is a specification.

Multistage turbines of the jet or impact type as ordinarily constructed have either one or more rows of wheel-buckets per stage, with nozzles for converting the pressure into velocity and discharging it against the buckets. When constructed with only one row of wheel-buckets, it necessitates a diaphragm or wall between each two rows. This construction involves a large number of diaphragms or separating-walls, which, in addition to being expensive to construct, increase the longitudinal dimension of the turbine, besides adding greatly to the weight. When constructed with two or more rows of wheel-buckets per stage, intermediate buckets are required between each two rows of buckets. These intermediate buckets receive motive fluid from one row of buckets and after changing its direction discharge it at the proper angle against the adjacent row of buckets, and so on. Since these buckets act merely as directing devices, they consume a certain amount of energy, and therefore represent a loss in efficiency.

The present invention has for its object to improve the construction of elastic-fluid turbines, whereby the advantages of stage operation are obtained without the disadvantage of using a large number of diaphragms, on the one hand, or a considerable number of intermediate buckets, on the other.

In carrying out one form of my invention a suitable casing is employed which is provided with one or more diaphragms between the high-pressure stages, wherein the difference in pressure is considerable. In these stages one or more rows of wheel-buckets are provided for abstracting energy from the motive fluid delivered by the preceding nozzle. Where two or more rows of wheel-buckets are employed in each stage, a row of intermediate buckets is provided, which cover the necessary number of wheel-buckets. I prefer to so arrange the parts in this particular embodiment of the invention that the wheels separated by the diaphragm or walls abstract

the energy of the motive fluid represented by the drop in pressure from the source of supply to atmosphere; but the invention is not to be construed as so limited, since the drop in pressure may be greater or less, as is best suited to meet the conditions of service. In the construction described the high-pressure nozzle or nozzles have a greater ratio of expansion than the low-pressure nozzles, the object being to reduce the stage-pressure to a point where the strains on the casing are well within the safe working limit. This results in a somewhat higher velocity of the motive fluid in the high-pressure stage or stages, and for this reason a greater number of rows of wheel-buckets is employed therein than in the low-pressure stages.

The low-pressure portion of the machine, or that designed to work between the terminal pressure of the stages above referred to and the exhaust, whether it be atmospheric or that due to a condenser, is of special construction. As many wheels or rows of wheel-buckets are provided as are necessary to fractionally abstract by stages the remaining energy due to the difference in terminal pressures. The buckets may be arranged on a drum in concentric rows, or they may each be mounted on a separate wheel and the several wheels connected by cylindrical flanges formed thereon or by rings which are located between the wheels. The main considerations are to cut off the space between the wheel-webs to form chambers, to strengthen the rotating member as a whole, and to reduce the cubical contents of the surrounding chamber as much as possible. This arrangement is also highly advantageous, in that it prevents individual movement of the wheels in any direction. Situated adjacent to each row of wheel-buckets is a ring which extends around the wheel and contains one or more nozzles that impart a certain amount of velocity to the steam or other elastic fluid and discharge it against the buckets. Each ring, in addition to containing or carrying the nozzle or nozzles, acts as a wall which cooperates with a wheel to form a stage or wheel compartment. As shown, the nozzles or nozzle sections or passages are formed in the ring-like structure which surrounds the wheel. Each nozzle-orifice may be provided with a well-rounded bowl anterior to the

throat, or several orifices may be grouped together and supplied from a single bowl. The nozzle-passages between the throat and the discharge-orifice may be expanding or non-expanding in character. This depends largely on the desired velocity of the fluid stream. The ring-like structure in which the nozzles or passages are formed or supported is seated on a shoulder on the casing and is retained by suitable means located inside or outside of the casing, as desired. If desired, it can be formed integral with the inner wall of the casing, in which case it would partake of the nature of a shoulder. When formed integral with the casing, the latter would of necessity be made in sections. The arc of the wheel covered by the nozzle-orifices increases from the inlet toward the exhaust, the last orifices covering the total or practically the total bucket area of the wheel. It is desirable to utilize the total bucket area of the wheel, since this wheel is the limiting feature in the design; but in some instances structural considerations will prevent. On the other hand, it may be desirable to leave some space to form a passage to balance the pressures on opposite sides of a row of buckets and their support. The portion or portions of each ring between the nozzles or nozzle-sections is left blank, so that a wall is formed which will restrict the passage of motive fluid through the clearances. The metal adjacent to the nozzle-orifices on the shaft side also acts as a part of the wall for separating one wheel-compartment from the next. In other words, the clearance between the wall and buckets or wheel-body forms a high-resistance path, while the nozzle or nozzle sections or passages and the working passages between buckets forms a low.

It is further to be noted that any fluid, excluding that which passes through the nozzle, in order to escape from one compartment to the next must pass through the buckets, and while it may not do the maximum amount of work it will do some, and in this manner even the leakage is made use of.

Another advantage residing in the use of these rings is that the plane flat surfaces of the wall between and adjacent to the discharge-orifices act to reduce the rotation losses.

As an illustration, with the structure referred to a turbine having six or more stages can be made with only two diaphragms and two sets of intermediates.

When owing to the special arrangement of parts a considerable difference in pressure exists between opposite sides of the low-pressure portion of the turbine, I may provide one or a number of valved or unvalved conduits for equalizing the pressures wholly or in part. These valves may be operated automatically or by hand, as preferred. In this form of my invention the pressure between

stages is equalized by sections—that is to say, one portion of the revolving element of the turbine is largely balanced by another.

In another embodiment of my invention I divide the high-pressure portion of the turbine-casing into stages by one or more diaphragms which contain or support nozzles. In the compartments thus formed are placed wheel structures of the same or substantially the same construction as previously described. Between each two rows of wheel-buckets is situated a ring-like support carrying nozzles or having nozzles formed therein, which supports and nozzles operate in the manner set forth above. Where the difference in pressure on opposite sides of the wheels is too great, the wheels may be perforated at one or more points; but I prefer not to do so on account of leakage. With this construction the intermediate buckets are entirely dispensed with.

The modified construction just described has this additional advantage: that the wheel or wheels as a whole can be lowered a sufficient amount by dropping the step or thrust bearing in a vertical machine or moving the shaft longitudinally in a horizontal machine to compensate for any wheel or casing distortion which may exist. In the first-mentioned arrangement involving intermediates the longitudinal movement of the shaft is of course limited by the small amount of the clearances. A turbine constructed according to the second modification of my invention can be divided into eight or more stages with the use of only two diaphragms and without intermediates.

A further embodiment of my invention contemplates dividing the turbine-casing into two compartments by means of a single wall or diaphragm and subdividing the compartments thus formed by arranging a number of rows of wheel-buckets on a suitable support after the manner described. Between each two rows of wheel-buckets is placed a nozzle of the same general character as before, the cross-sectional area of the nozzle discharge-orifices increasing from the supply toward the exhaust. The arrangement of the parts is such that each nozzle is arranged in a compartment by itself and the motive fluid is renozzled every time it passes through a row of buckets. By using a single diaphragm the end pressure or thrust to which the shaft would or might be subjected is reduced. In the construction just described the effect of an eight-stage machine is obtained with only a single diaphragm. In certain cases—as, for example, where the tendency to end thrust is small or where compensating means are provided, such as would be the case where the end thrust on one part of the machine balanced the other part wholly or partially—I may omit the diaphragm altogether. In this latter case the

arrangement of the nozzles and buckets would be such as to produce rotation in the same direction and the number of stages with suitable nozzles made anything that is desired.

5 I have described my invention in connection with wheels which revolve in the same direction; but certain of the wheels may revolve in one direction and the remainder in the opposite.

In the accompanying drawings, which illustrate one embodiment of my invention, Figure 1 is an axial section of a vertical turbine of the jet type. Fig. 2 is a partial axial 15 section of a turbine, illustrating a modified construction wherein the intermediates are dispensed with. Fig. 3 is a sectional view of a further modification wherein only a single diaphragm is employed, and Fig. 4 is a sectional view of a part of a turbine.

Referring to Fig. 1, 1 represents the casing of a machine, which is mounted upon a base 2, the latter containing a chamber 3, which is connected to or forms a part of a condenser. 25 4 represents a conduit for conveying the exhaust from the machine. The upper end of the casing is provided with a cover or head 5, which is bolted or otherwise secured to a casing. The shaft 6 is disposed vertically, 30 and mounted thereon are high-pressure wheels 7 and 8. These are separated by a diaphragm 9. The wheel 8 is separated from the lower-pressure wheels by a diaphragm 10. Situated below the diaphragm 35 10 are low-pressure wheels 11. Each of these wheels is provided with a cylindrical projection 12, that forms a part of a wall to cut off the space 13 between the wheels from the surrounding chamber. As many of 40 these wheels are employed as are necessary to abstract the energy from the motive fluid. The end wheels are provided with a cylindrical wall 12 on one side only; but the other wheels are provided with these walls on both 45 sides. The wall on one wheel is rabbeted into the corresponding wall on the other wheel. Extending axially through the wheels and the cylindrical walls are retaining-bolts 14 or equivalent devices. Each of 50 the low-pressure wheels is provided with a single row of buckets 15, the buckets being provided with integral projections, which enter a groove in the periphery of the wall and are retained in place by pins or bolts. The 55 upper row of buckets is situated directly under the diaphragm 10 and receives motive fluid from the nozzles formed therein or supported thereby. Mounted below the first row of buckets is a cylindrical or ring-like structure 60 16, which is located in close proximity to the upper side of the row of buckets 17 and also to the upper side of the wheel-body. In the cylindrical or ring-like structure or carried thereby are nozzle-passages which receive motive fluid from the preceding wheel

and after converting a certain amount of the pressure into velocity discharge it against the bucket 17. The nozzle or orifices in this structure extend only partially around the wheel, and the portion of the ring between 70 the nozzle-orifices is made as smooth as possible, so as to coöperate with the upper side of the wheel and the buckets to form a stage. The portion of the cylindrical or ring-like structure just referred to, which is located 75 in close proximity to the wheel-buckets, is given reference-numeral 18. In addition to forming a part of the stage the cylindrical structure also tends to reduce the rotation losses by presenting a smooth surface in 80 close proximity to the wheel-buckets. The succeeding ring-like structures 16 after the first are of the same construction and operate in the same manner, the exception being that the nozzle area increases in each succeeding 85 stage.

In case of a material difference in pressure between the first and second stages of the low-pressure portion of the turbine or between other portions a conduit 19 may be provided, 90 which communicates with the upper side of the first wheel and with the under side of the second or a succeeding wheel. The conduit may be provided with a valve 20 or not, as desired.

95 It is to be noted that the high-pressure stages are provided with two rows of wheel-buckets, while each of the low-pressure stage-buckets is provided with only one row of wheel-buckets. In the former case intermediate buckets 21 are provided for reversing the direction of the motive fluid between the buckets. Steam or other elastic fluid is supplied to the turbine by inlet-nozzles 22, which cover only a fraction of the bucket 100 area. These nozzles are supplied with fluid from the chest 23, and the passage of fluid to the nozzles is controlled by a plurality of separately-actuated valves 24, each of the valves being independent in its action of 105 every other valve and responding to changes in position of a speed-responsive device. I may control only the supply of motive fluid to the first stage, or I may control the supply to the first stage and also to one or more of 110 the succeeding stages.

115 In Fig. 2 I have shown a modification of my invention wherein the use of intermediates is entirely obviated. The construction of the wheels is the same as that described in 120 connection with the low-pressure wheels of the turbine shown in Fig. 1, except that openings or passages 25 are provided for equalizing the pressure on the opposite sides of the wheels. In some cases these openings or 125 passages can be omitted, and wherever it is possible I prefer to do so. Between each two rows of wheel-buckets is a ring-like structure 26, which coöperates with the upper side of the rows of wheel-buckets and 130

the body of the wheel to form a stage. This ring-like structure also contains nozzle-passages or has nozzles bolted or otherwise attached thereto. A modified form of inlet-nozzle is also provided, which nozzle extends through an opening in the side wall of the casing 1 and is provided with an outside flange 27. The nozzle is held in place by bolts 28, which extend through slots in the flange, the object of this arrangement being to permit the nozzle to be adjusted in an axial direction. Steam or other motive fluid is supplied to the nozzle by the conduit 29. I may provide each of the nozzle-sections with a valve or not, as desired.

In the present embodiment of the invention only two diaphragms 30 and 31 are provided. In this instance the first four rows of wheel-buckets are contained in the high-pressure portion of the turbine, while the last four are contained in the low-pressure portion. With this arrangement I get the advantages of an eight-stage turbine with only two diaphragms.

In Fig. 3 I have shown a modification wherein only one diaphragm 32 is provided, which diaphragm is similar in construction to those previously described and which may divide the turbine into parts at the atmospheric line. Steam or other elastic fluid is supplied to the first wheel by a nozzle 33 of the same general construction as described in the previous figure. In this case, as in Fig. 2, the intermediates are dispensed with, so that the wheel structure as a whole can be adjusted vertically over a considerably wider range than where intermediate buckets are employed. This arrangement is advantageous in those cases where for any cause there is excessive distortion of the wheel, casing, or other parts due to heat.

The ring-like structures 34, which divide the turbine into stages and also support the nozzles and reduce rotation losses, may be let into grooves formed in the casing 1, or they may be mounted upon internal shoulders, as desired. The rings may either be made in a single piece or of sections. It is preferable to make them of sections, so that they can be more readily assembled and taken down.

In Fig. 4 is shown a desirable arrangement for the head 5 or diaphragm or wall between stages, where such a construction is employed. It is situated in close proximity to the web of the wheel, thereby cutting down the cubical contents of the chamber as much as possible and also reducing the rotation losses. To the wheel-chamber at a point near the shaft is connected a conduit 35, which discharges into a wheel-compartment of lower pressure, preferably the adjacent compartment, so as not to have too great a pressure difference. This conduit 65 will tend to equalize the end thrust on the

shaft. It is of even greater use with the constructions employing the ring-like-nozzle arrangements previously described.

In accordance with the provisions of the patent statutes I have described the principle of operation of my invention, together with the apparatus which I now consider to represent the best embodiment thereof; but I desire to have it understood that the apparatus shown is only illustrative and that the invention can be carried out by other means.

What I claim as new, and desire to secure by Letters Patent of the United States, is—

1. An elastic-fluid turbine comprising a casing, rows of wheel-buckets, and inlet-nozzles, in combination with wheel-webs for carrying the buckets, a cylindrical wall on each web which unites the rows of wheel-buckets, a ring-like structure which extends toward the wall but does not contact therewith, the 70 said structure coöperating with a row of wheel-buckets to form a stage, and expanding nozzles in said structure which convert the fluid-pressure in one stage into velocity and discharge it against the wheel-buckets in 75 a stage of lower pressure.

2. In an elastic-fluid turbine comprising a casing, rows of buckets, and inlet-nozzles, in combination with wheel webs or bodies for carrying the buckets, cylindrical walls on 80 said webs which engage one with the other, means for clamping the wheel-webs together, a ring-like structure which extends between adjacent rows of wheel-buckets and coöperates with one of the rows to form a stage, and 85 a nozzle for discharging fluid against the row of wheel-buckets coöperating with said structure.

3. In an elastic-fluid turbine, the combination of a casing, a shaft, bucket-wheels 95 mounted thereon, means for dividing the casing into compartments or stages in such manner that a high-pressure compartment or stage contains more rows of wheel-buckets than does a low-pressure compartment or 100 stage, intermediate buckets for the high-pressure stage only, and nozzles for discharging fluid under a predetermined condition as to pressure and velocity against the wheel-buckets.

4. In an elastic-fluid turbine, the combination of a casing, means for dividing it into compartments or stages, wheel and intermediate buckets located in a high-pressure stage for fractionally abstracting energy 110 from the motive fluid, a single row of wheel-buckets in each of the low-pressure stages, and nozzles for discharging fluid against the buckets of the different stages.

5. In an elastic-fluid turbine, the combination of a casing, a diaphragm which divides the casing into compartments, wheels carrying buckets located in the compartments, rings supported by the casing which coöperate with the wheels to divide the compartments.

ments into additional compartments, and nozzles which convert the pressure of the motive fluid into velocity and discharge it against the wheel-buckets.

5 6. In an elastic-fluid turbine, the combination of a casing, a diaphragm which divides the casing into compartments, wheels carrying buckets located in the compartments, rings supported by the casing, the wheels and 10 rings coöperating to form stages and presenting smooth flat surfaces to each other and in close proximity to reduce leakage, and nozzles, each comprising a plurality of passages, which are supported by the rings and 15 discharge motive fluid against the wheel-buckets.

7. In an elastic-fluid turbine, the combination of a casing, a shaft located therein, bucket-wheels mounted on the shaft, a diaphragm which divides the casing into compartments and is supported at its periphery by the wheel-casing and is provided with an orifice to receive the hub of a wheel, rings which are supported by the casing, and coöp-

erate with the wheels at points remote from the hubs to form stages and also to reduce the rotation losses by presenting smooth surfaces to the idle buckets, and nozzles for discharging motive fluid against the wheel-buckets.

8. In an elastic-fluid turbine, the combination of a casing, a diaphragm which divides the casing into high and low pressure compartments, a plurality of rings located within the casing on the low-pressure side of the diaphragm, wheels for the high and low compartments, the wheels in said low-pressure compartments coöperating with surfaces on the rings to form low-pressure stages, admission-nozzles, and nozzles which receive motive fluid from one stage and discharge it against the wheel-buckets in another stage.

In witness whereof I have hereunto set my hand this 26th day of May, 1904.

OSCAR JUNGGREN.
